Primary Examiner — Susan Bennett Hattan*Assistant Examiner* — Lauren D McVey(57) **CLAIM**

The ornamental design for a toner cartridge, as shown and described.

DESCRIPTION

FIG. 1 is a front, right side, top perspective view of a toner cartridge, showing our new design;
FIG. 2 is a rear, left side, top perspective view thereof;
FIG. 3 is a front, left side, bottom perspective view thereof;
FIG. 4 is a rear, right side, bottom perspective view thereof;
FIG. 5 is a front elevation view thereof;
FIG. 6 is a left side elevation view thereof;
FIG. 7 is a rear elevation view thereof;
FIG. 8 is a right side elevation view thereof;
FIG. 9 is a top plan view thereof; and,
FIG. 10 is a bottom plan view thereof.

The broken lines immediately adjacent to the shaded areas represent the bounds of the claimed design while all other broken lines are directed to environment and are for illustrative purposes only; the broken lines form no part of the claimed design. In addition, the unshaded surfaces that directly adjoin the claimed solid lines form no part of the claimed design.
